(57) CLAIM

The ornamental design for indicia on a container as shown and described.

DESCRIPTION

FIG. 1 is a perspective view of indicia on a container, embodying our new design;

FIG. 2 is a top plan view thereof;

FIG. 3 is a bottom view thereof;

FIG. 4 is a left side view thereof;

FIG. 5 is a right side view thereof;

FIG. 6 is a front view thereof; and,

FIG. 7 is a back view thereof.

The broken lines shown in the drawings are for illustrative purposes only and form no part of the claimed design.
